REED TRIMMER

Jules Miller, Camden, N. J.

Application April 28, 1937, Serial No. 139,618

1 Claim. (Cl. 30—229)

This invention relates to reed trimmers, and its general object is to provide a device of that character for cutting or trimming the reeds of wind musical instruments, such as clarinets, 5 saxophones and the like, to restore the tip of the reeds to their proper shape or curvature, in an easy and expeditious manner, and with minimum effort on the part of the user.

A further object is to provide a reed trimmer 10 that is capable of cutting reeds of various sizes for use with different instruments, such as a B flat clarinet, an E flat alto saxophone, a B flat tenor saxophone and an E flat baritone saxophone, thereby overcoming the necessity of employing a plurality of trimmers, one for the reed of each instrument, which of course is a handicap on a musician who plays all of the instruments mentioned, as he must possess and maintain a number of trimmers for use, when necessary or 20 desired.

A further object is to provide a trimmer, that is capable of performing its intended function for a prolonged period of time, without damage or breakage thereto, is simple in construction, inexpensive to manufacture and extremely efficient in operation, use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing where- 35 in like characters denote like or corresponding parts throughout the several views, and in which:

Figure 1 is a front view of the trimmer which forms the subject matter of the present invention.

Figure 2 is a sectional view taken approximate- 40 ly on line 2—2 of Figure 1, looking in the direction of the arrows and illustrates my trimmer in use.

Figure 3 is a vertical sectional view with the lever member in closed position.

Referring to the drawing in detail, the reference numeral 1 indicates the body of my trimmer which as shown is in the form of a rectangular plate that is relatively thin, and made from any material suitable for the purpose, such as Swedish spring steel. The plate is preferably 50 provided with round corners as shown.

The plate is stamped or cut in any well known manner to provide cutting arms 2 extending transversely thereof and disposed in equi-dis- tantly spaced relation with respect to each other.

55 The sides of the arms 2 are spaced from the body

of the plate by slots 3 formed in the latter, and while one of the ends of the arms is integral with the body, their opposite ends are free and enlarged, as well as curved as at 4 in convexed formation, to cooperate with concaved edges 5 of the body to set up a shearing action, it being obvious that the concave and convex portions provide cutting edges, as clearly shown in Figures 2 and 3. The cutting arms or members 2 are normally spaced at an outward inclination with respect to the plane of the body, as shown in Figure 2, and will be noted from Figure 1, that the arms are of different widths, while the companion cutting edges 4 and 5 are of different lengths, to provide cutting means for reeds of 15 various sizes for use with different instruments, the cutting means on the extreme left hand side of Figure 1 being for use on a reed for a B flat clarinet, the one next thereto for a reed for an E flat alto saxophone, the next for a reed for a 20 B flat tenor saxophone and the last for a reed for an E flat baritone saxophone.

Cooperating with the arms for moving the convexed cutting edges in shearing association with the concaved cutting edges, is a lever member 6 that is co-extensive with the length of the body plate, and is bent upon itself to form a channel and companion clamping portions 7 and 8 for clamping association with the opposite sides of the body plate, the portions being of a width to extend beyond the cutting edges 4, as clearly shown in Figure 3. The lever is pivotally secured to the body plate adjacent one end thereof, by a pivot pin 9, for movement as will be apparent, and the clamping portion 8 is outwardly flared as at 10 along the entire length thereof, for the purpose of receiving and guiding the cutting edges 4 toward the cutting edges 5 to provide the shearing action, as will be obvious upon inspection of Figure 3.

In the use of my trimmer, a reed such as indicated by the letter A is disposed against the proper cutting arm, as shown in Figure 2, with the tip thereof extending beyond the cutting edge 4. The lever 6 is then moved to closed position, which will result in the outwardly flared portion or flange 10 engaging and moving the arm between the clamping portions and the cutting edge 4 thereof then cooperates with its companion cutting edge 5 to shear the tip, as will be apparent, consequently it will be seen that the reed is accurately trimmed to provide a tip of the proper shape and curvature.

It is thought from the foregoing description 55

that the advantages and novel features of the invention will be readily apparent.

It is to be understood that changes may be made in the construction and in the combination and arrangement of the several parts, provided that such changes fall within the scope of the appended claim.

What I claim is:

A reed trimmer comprising a rectangular metallic body plate cut to provide concaved cutting edges of various lengths and spring arms having convexed cutting edges for fitting association with the concaved cutting edges for co-

operation therewith, said arms being normally inclined for disposal at an angle to the plane of the body plate, a clamping lever co-extensive with the length of the body plate and channeled to provide clamping portions for fitting association with the opposite sides thereof, an outwardly flared flange formed on one clamping portion and engageable with the arms for disposing the latter between the clamping portions to move the convexed cutting edges in cutting position 10 with the concaved cutting edges to provide a shearing action.

JULES MILLER.
